(57) **CLAIM**

We claim the ornamental design for a mobile hotspot device having a cylindrical battery pack and integrated kickstand, substantially as shown and described.

DESCRIPTION

FIG. 1 is a first perspective view of a mobile hotspot device having a cylindrical battery pack and integrated kickstand, wherein the integrated kickstand is oriented in an aligned position, illustrating the claimed design;

FIG. 2 is a top view of a mobile hotspot device having a cylindrical battery pack and integrated kickstand, wherein the integrated kickstand is oriented in an aligned position, illustrating the claimed design;

FIG. 3 is a bottom view of a mobile hotspot device having a cylindrical battery pack and integrated kickstand, wherein the integrated kickstand is oriented in an aligned position, illustrating the claimed design;

FIG. 4 is a frontal view of a mobile hotspot device having a cylindrical battery pack and integrated kickstand, wherein the integrated kickstand is oriented in an aligned position, illustrating the claimed design;

FIG. 5 is a rear view of a mobile hotspot device having a cylindrical battery pack and integrated kickstand, wherein the integrated kickstand is oriented in an aligned position, illustrating the claimed design;

FIG. 6 is a first side view of a mobile hotspot device having a cylindrical battery pack and integrated kickstand, wherein the integrated kickstand is oriented in an aligned position, illustrating the claimed design;

FIG. 7 is a second side view of a mobile hotspot device having a cylindrical battery pack and integrated kickstand, wherein the integrated kickstand is oriented in an aligned position, illustrating the claimed design; and,

FIG. 8 is a second perspective view of a mobile hotspot device having a cylindrical battery pack and integrated kickstand, wherein the integrated kickstand is oriented in a rotated position, illustrating the claimed design.

The broken lines immediately adjacent the shaded areas represent the bounds of the claimed design while all other broken lines are directed to environment and are for illustrative purposes only; the broken lines form no part of the claimed design.
